[57] **CLAIM**

The ornamental design for a record disc player system or similar article, substantially as shown and described.

DESCRIPTION

FIG. 1 is a top plan view of a record disc player system or similar article showing my new design;

FIG. 2 is a right side elevational view thereof;

FIG. 3 is a rear elevational view thereof;

FIG. 4 is a front elevational view thereof;

FIG. 5 is a bottom plan view thereof;

FIG. 6 is a left side elevational view thereof;

FIG. 7 is a top and right side perspective view of the system with the upper portion raised; and

FIG. 8 is a front, top and right side perspective view with a record disc shown in broken lines for convenience of illustration.

FIG. 1

FIG. 2

FIG. 4

FIG. 3

FIG. 5

FIG. 6

FIG. 7

UNITED STATES PATENT AND TRADEMARK OFFICE
CERTIFICATE OF CORRECTION

PATENT NO. : Des. 279,775

DATED : July 23, 1985

INVENTOR(S) : Mitsuo Nemoto

It is certified that error appears in the above-identified patent and that said Letters Patent is hereby corrected as shown below:

On the title page

In the list of inventors, change "Mitsuo Nemoto,
Machida, Japan" to --Mitsuo Nemoto, Tokyo, Japan--.

In the reference section cited, change "Iwadka et al."
to --Iwaoka et al.--

Signed and Sealed this

Tenth Day of December 1985

[SEAL]

Attest:

DONALD J. QUIGG

Attesting Officer

Commissioner of Patents and Trademarks
